HAMMER ACTUATING MECHANISM

Aldo Robert Filippi, Redwood City, Calif.

Application March 20, 1950, Serial No. 150,790

5 Claims. (Cl. 1-47)

1

This invention relates to an improved hammer actuating mechanism.

The present invention provides an electrically operated hammer for driving nails, spikes or the like. The hammer is actuated downwardly with considerable force by means of a heavy compression spring and its upward return movement is effected by a motor operated cam. The operation of the hammer is controlled by means of an easily manipulated hand grip, thereby making it possible to commence or discontinue the up and down movement of the hammer whenever desired. The hammer is intermittently released for instantaneous movement in a downward direction by a circularly moving cam which is so constructed and arranged that it slowly raises the hammer after its striking operation is completed and then abruptly releases it so the charged tension spring may again actuate it downwardly.

The primary object of the present invention is to provide an electrically operated hammer of the kind characterized, embodying novel means for controlling its operation.

Other and further objects of my invention will be pointed out herein, or will be indicated in the appended claims, or will be obvious to one skilled in the art upon an understanding of the present disclosure. For the purpose of this application I have elected to show herein certain forms and details of an electric hammer representative of my invention; it is to be understood, however, that the embodiment of my invention herein shown and described is for the purpose of illustration only, and that therefore it is not to be regarded as exhaustive of the variations of the invention.

In the accompanying drawings:

Fig. 1 is a front elevational view of an electric hammer embodying my invention;

Fig. 2 is a plan view of the same;

Fig. 3 is a sectional view taken vertically through the cam wheel and showing the cam arm in an elevated position;

Fig. 4 is a sectional view taken on the line 4-4 of Fig. 2, showing portions of the cam wheel broken away;

Fig. 5 is a diagrammatic detailed view taken on the line 5-5 of Fig. 3, showing the position of the cam when the hammer arm is in a raised position;

Fig. 6 is a detailed sectional view showing portions of the hammer arm and its associated stop wheel; and

Fig. 7 is a sectional view taken on the line 7-7 of Fig. 4.

2

Referring to the drawings the numeral 1 designates a supporting frame or base which is mounted on spherical members 2 or other similar means which facilitates the movement of the machine from place to place. Pivotally supported between its ends on a shaft 3 that is journaled on trunnions 4 is a hammer arm 5 which is arranged for up and down pivotal movement. The hammer arm 5 carries a hammer 6 at its outer end which is adapted to travel through an arcuate path when moving upwardly and downwardly during a nail or spike driving operation. For illustration purposes a nail holding device 7 is shown in a position for striking engagement by the hammer. A heavy helical compression spring 8 is arranged to urge the rear end of the hammer arm 5 upwardly and the hammer 6 downwardly. The spring 8 is mounted on and positioned between two spaced discs 9, the lower of which is provided with a socket for receiving a ball 10 carried by an adjusting screw 11. The adjusting screw is threaded through an opening in the base 1, and an enlargement at its lower end provides convenient means for turning it to adjust the tension of the spring 8. The upper plate 9 with which the spring engages is provided with a spherical protuberance 12 which fits in a socket formed in a boss carried at the rear end of the hammer arm 5. The ball and socket arrangements above described make it possible for the spring 8 to automatically adjust its position as the rear end of the hammer arm moves up and down. The hammer arm 5 is shown as comprising three integrally joined sections which are not in alignment, but such a shape is not essential to the operation of the machine since the arm may be straight, curved or otherwise suitably shaped. The helical tension spring 8 exerts sufficient pressure in an upward direction on the rear end of the hammer arm 5 to cause the hammer 6 to move downwardly with a considerable striking force when the said arm is released from its raised position.

Supported on trunnions 13 secured to the base 1 is a drive shaft 14 which is operatively connected by suitable reduction gear and shaft connections 15 to the drive shaft 16 of an electric motor 17. The shaft 14 rotates continuously in a counterclockwise direction (Figs. 4 and 5). Keyed to the drive shaft 14 is a cam wheel 18 which extends vertically alongside the hammer arm 5. Loosely mounted on the drive shaft 14 is a cam 19 which is formed with an arcuate slot 20 within which a pin 21 secured eccentrically to the cam wheel 18 loosely fits. The arcuate slot 20 in the cam 19 is concentrically arranged

with respect to the drive shaft 14 and the cam wheel 18. The cam 19 is arranged alongside the cam wheel 18 in a position underlying and engaging with the hammer arm 5. As the cam wheel 18 rotates the pin 21 engaging with the leading end of the arcuate slot 20 carries the cam 19 in a circular counterclockwise direction (Figs. 4 and 5). The cam is so shaped that it slowly raises the forward portion of the hammer arm 5 and the hammer 6 to elevated positions preparatory to their downward striking operation. The cam 19 and its arcuate slot 20 are so shaped that when the cam reaches a position in which the hammer arm 5 is at the upper extremity of its upward movement, it will be swung at an accelerated speed in a counterclockwise direction by the downward pressure of the hammer arm thereon. By reason of the shape and position of the slot in the cam 19, the said cam is free to move with accelerated speed after its trailing end reaches a position where it no longer supports the hammer arm. When the cam 19 thus assumes a position in which it no longer restrains the hammer arm 5 and the hammer 6 from being moved downwardly by the compression spring 8, the said hammer arm and hammer immediately commence their downward stroke. This occurs after the cam has been carried slightly beyond the position shown in Fig. 5. The cam 19 being free to rotate independently of the shaft 14 drops downwardly to a position in which it does not interfere with the completion of the downward stroke of the hammer arm and hammer. The continued rotation of the cam wheel 18 carries the pin 21 through the length of the arcuate slot 20 in the cam 19, and with the said pin again engaging with the leading end of the arcuate slot the cam is rotated to a position where it again exerts an upward lifting pressure on the hammer arm.

The operation of the hammer is controlled by the mechanism now to be described.

Secured to the drive shaft 14 is a hammer stop wheel 22 which is so connected to the said shaft by a longitudinal key-way and key that it may be shifted back and forth toward and away from the cam wheel 18. The hammer stop wheel 22 is formed with an annular peripheral groove or channel 23 within which a downwardly projecting pin 24 secured to the hammer arm 5 may become positioned. The pin 24 is admitted to the peripheral channel 23 through an opening or slot 25 (Fig. 2) in the inner peripheral flange of the hammer stop wheel 22 when the latter is shifted toward the cam wheel 18. The pin 24 may enter the channel 23 of the hammer stop wheel 22 when the hammer arm 5 has reached the height where the said pin is horizontally aligned with the slot 25 and when the hammer stop wheel is suitably shifted along the drive shaft 14 to allow the said pin to enter the said channel through the said slot. The entry of the pin 24 through the slot 25 into the peripheral channel 23 of the hammer stop wheel 22 is effected when the said wheel has rotated sufficiently to bring the slot into a position directly opposite the said pin. When the pin 24 has become positioned in the peripheral channel 23 of the hammer stop wheel 22 it rides on the periphery of the said wheel and thereby holds the hammer arm 5 in an inactive raised position. By shifting the hammer stop wheel 22 in the opposite direction and away from the cam wheel 18 the pin 24 of the hammer arm moves through the slot 25 (Figs. 2 and 6) to a disengaging posi-

tion with respect to the periphery of the hammer stop wheel, thereby allowing the hammer arm 5 and the hammer 6 to again resume their up and down movement.

The hammer stop wheel 22 is formed with a hub portion 22' which is also formed integrally with a circular flange 26, the said flange being suitably spaced from the hammer stop wheel to permit the forked end of a lever 27 to be positioned between the said wheel and the flange. The forked end of the lever 27 rests at one end on the hub portion 22' of the hammer stop wheel 22 and its opposite end is engaged and supported by a stop 28 (Fig. 2) secured on the motor 17 or on the frame or base 1. A coiled compression spring 29 arranged between a non-shiftable stop collar 30 and the flange 26 urges the said flange, the hub portion 22' and the hammer stop wheel 22 toward the cam wheel 18. Pivoted between its ends as at 31 on a supporting member 32 secured on the base 1, is a control lever member 33. The upper end of the control lever 33 is connected by means 34 to the forked lever 27 while its lower end is connected by a cable 35 to one end of a hand grip lever 36. The hand grip lever 36 is pivoted at one end as at 37 on a stationary support 38. By pulling the hand lever 36 outwardly in a direction away from the base 1 the forked end of the lever 27 is moved against the pressure of the spring 29 in a direction away from the cam wheel 18, thereby exerting a pressure in the same direction on the flange 26. The said flange, the hub portion 22' and the hammer stop wheel 22 are all shifted along the drive shaft 14 in the same direction, thereby allowing the hammer arm pin 24 to be released from engagement with the periphery of the said hammer stop wheel. The hammer arm 5 and the hammer 6 thereupon resume their up and down movement. When the operation of the hammer is to be again discontinued the hand grip lever 36 is released, thereby allowing the compression spring 29 to return the cam stop wheel 22 to a position whereby the hammer arm pin 24 may again enter the annular peripheral groove 23 and ride on the periphery of the said cam stop wheel.

What I claim is:

1. In an electrical hammer, a rigid hammer arm mounted between its ends for pivotal movement about a substantially horizontal axis, a hammer carried on the forward end of the arm, spring means urging the forward end of the hammer arm and the hammer downwardly, a drive shaft extending beneath the hammer arm, a cam mounted on the drive shaft and arranged beneath and in engagement with the hammer arm, means coupled with the cam and actuated by the drive shaft for rotating the cam, whereby the forward end of the hammer arm and the hammer may be actuated upwardly against the pressure of the spring, and control means for releasably holding the forward end of the hammer arm and the hammer in a raised position.

2. In an electric hammer, a hammer arm carrying a hammer at its forward end, the said hammer arm being arranged to swing about a substantially horizontal pivot, spring means urging the forward portion of the hammer arm and the hammer downwardly, a drive shaft, a cam wheel keyed to the drive shaft, a cam loosely mounted on the drive shaft adjacent the cam wheel and having an arcuate concentric slot, and a projecting pin carried eccentrically by the cam wheel and arranged in the slot, the said cam having a cam surface arranged to engage with

the lower side of the hammer arm, and the said cam being constructed and arranged to raise the forward portion of the hammer arm and hammer to a predetermined position and then abruptly disengage the said hammer arm.

3. In an electric hammer, a hammer arm having a hammer secured to its forward end, the said hammer arm being pivotally mounted to swing up and down, spring means urging the forward portion of the hammer arm and hammer downwardly, a drive shaft, a cam wheel keyed to the drive shaft, a cam loosely mounted on the drive shaft, means operatively connecting the cam and the cam wheel, the said cam having a cam surface arranged to engage with the underneath side of the hammer arm, and the said cam being constructed and arranged to raise the forward end portion of the hammer arm to a predetermined position and then to abruptly disengage said hammer arm.

4. In an electric hammer, a hammer arm having a hammer secured to its forward end, the said hammer arm being pivotally mounted to swing up and down, spring means urging the forward end portion of the hammer arm and the hammer downwardly, a drive shaft, a cam wheel keyed to the drive shaft, a cam loosely mounted on the drive shaft and coupled to the cam wheel, the said cam being arranged to raise the forward end portion of the hammer arm to a predetermined height against the pressure of the spring means and then abruptly release the said arm, and control means for intercepting and releasably holding the hammer arm while in its said raised position.

5. In an electric hammer, a hammer arm hav-

ing a hammer carried on its forward end portion and having also a downwardly projecting member, the said hammer arm being mounted between its ends for up and down pivotal movement, spring means engaging the rear end portion of the hammer arm for urging the forward end portion thereof and the hammer downwardly, a drive shaft, a cam wheel keyed to the drive shaft, a cam loosely mounted on the drive shaft and coupled to the cam wheel, the said cam being constructed and arranged to engage with and raise the forward end portion of the hammer arm to a predetermined height against the pressure of the spring means and then abruptly release the said arm, a rotatable stop wheel keyed to but slideable back and forth on the drive shaft, the said stop wheel having annular means at its periphery for receiving and supporting the downwardly projecting member of the hammer arm, whereby the operation of the hammer arm may be discontinued, a spring urging the stop wheel toward the hammer arm, and hand controlled means for shifting the stop wheel against the pressure of the spring to a position whereby the projecting member of the hammer arm is free of the supporting means of the stop wheel.
